UNITED STATES PATENT OFFICE.

WILLIAM D. KELLY, OF JEFFERSON, TEXAS.

RAILROAD-TRACK BRACE.

No. 910,132.

Specification of Letters Patent.

Patented Jan. 19, 1909.

Application filed April 28, 1908. Serial No. 429,745.

To all whom it may concern:

Be it known that I, WILLIAM D. KELLY, a citizen of the United States, residing at Jefferson, in the county of Marion and State 5 of Texas, have invented a new and useful Railroad-Track Brace, of which the following is a specification.

This invention relates to rail braces and supports for use in connection with railway 10 ties and rails.

The object of the invention is to provide a device of this character which is designed to extend under and engage a rail at any desired point between the ties thereunder, said 15 brace being so constructed as to be readily fastened to one of the adjoining ties at a point between the rails by means of spikes or similar devices, the brace when thus positioned constituting efficient means for preventing lateral displacement of the rail and 20 for holding the rail against tilting.

Another object is to provide a simple form of brace which also operates sufficiently to support the rail should the same break from 25 any cause, thus reducing the danger of derailment.

Another object is to provide braces which serve to hold the rails at the desired angles relative to the ties to prevent the ties from 30 creeping longitudinally of the rails as often occurs from various causes.

With these and other objects in view the invention consists of certain novel features of construction and combinations of parts 35 which will be hereinafter more fully described and pointed out in the claims.

In the accompanying drawings is shown the preferred form of the invention.

In said drawings: Figure 1 is a plan view 40 of a brace embodying the present improvements, the same being shown in position upon a tie and rail. Fig. 2 is a section on line A—B, Fig. 1. Fig. 3 is a diagrammatical view showing the relative arrangements 45 of the rails, braces, and ties in the construction of a track.

Referring to the figures by characters of reference, 1 designates a strip formed of a metal capable of resisting severe strains and 50 said strip is provided at one end with a head 2 on which are formed two oppositely disposed pairs of rigid jaws 3 and 4, the jaws of each pair being spaced apart and the inner or adjoining ends of the jaws being 55 arranged along parallel lines. The lower portion of each jaw constitutes the working

face thereof and is undercut as indicated at 5 and the undercut portions of each two opposed jaws diverge outwardly toward the adjoining side edge of the strip 1 as indicated clearly by dotted lines at 5 in Fig. 1. The distance between the two pairs of jaws is slightly greater than the width of the base of a rail 6 and the diverging working faces 5 of the jaws are so arranged that when a rail is positioned between the jaws and the strip 1 is swung horizontally relatively thereto two diagonally opposed jaws 3 and 4 will bind upon opposite base flanges of the rail as shown in Fig. 1. Ears 7 extend in 65 opposite directions from the head 2 and between the ends of the jaws 3 and 4 and each of these ears is designed to receive a set screw 8 which, after the jaws have been clamped upon the rail, are screwed upwardly against 70 the base of the rail so as to further assist in 75 clamping the brace thereon.

That end of the strip 1 which is farthest removed from head 2 has a series of ears 9 extending from its longitudinal edges, each ear being provided with an opening 10 for the reception of a spike 11 or other securing device. One or more openings 12 may also be provided within the end portion of the strip 1 and between the ears 9. Strip 1 is 80 curved upwardly at an intermediate point as shown at 13 so that the lower surface of the apertured end thereof is disposed in the same plane with that surface of the head on which rail 6 rests. In order that the strip 85 may be reinforced at the curve 13 a longitudinal web 14 is formed upon its lower surface as shown particularly in Fig. 2.

When it is desired to brace a rail by means of the device herein described strip 1 is inserted under the rail and placed at right angles thereto and by raising said strip the jaws 3 and 4 will assume positions at opposite sides of the rail. The strip 1 is then swung horizontally onto one of the adjoining ties 15 until two diagonally opposed jaws 3 and 4 bind upon opposite base flanges of the rails, whereupon a desired number of spikes or other fastening devices 11 are driven through certain of the openings 10 located 95 above the tie 15, thus securely fastening the brace strip to the tie. The set screws 8 are then screwed upwardly against the bottom 100 of the rail.

As shown in Fig. 3 two braces are preferably attached to each tie, said braces extending 110 along diagonal lines in opposite direc-

tions and engaging the respective rails of the track. The rails and ties are thus securely held together at predetermined angles and it obviously becomes impossible for the 5 rails to spread or tilt or for the ties to creep longitudinally of the rails. Moreover, should either rail become broken at a point between two of the ties the brace engaging the rail will serve to support it and thus reduce 10 to the minimum the danger of derailment. It will be noted that it is not necessary to produce "rights" and "lefts", as the brace can be used upon either rail of the track. Moreover, it can be applied to rails 15 of a track already laid and will therefore be found especially desirable in strengthening tracks already in use particularly at points where they are subjected to severe strains.

Importance is attached to the fact that 20 when braces such as herein described are used ballast can be partly or entirely dispensed with, especially on bridges. This is particularly desirable on bridges and similar structures.

25 What is claimed is:

1. As a new article of manufacture means attachable to a tie for holding a rail in fixed relation thereto, said means comprising an elongated strip, and opposed pairs 30 of spaced rail engaging jaws located at one end of the strip:

2. As an article of manufacture means attachable to a tie for holding a rail in fixed relation to said tie, said means comprising 35 an elongated strip and opposed pairs of rail engaging jaws integral therewith, the two pairs of jaws being spaced apart a distance greater than the width of a rail base.

40 3. As an article of manufacture a rail brace comprising an elongated strip and oppositely disposed pairs of jaws integral with the strip, the two pairs of jaws being spaced apart a distance greater than the 45 width of a rail base and having undercut gripping faces.

4. As an article of manufacture a rail brace comprising an elongated strip and oppositely disposed pairs of jaws upon the 50 strip, the two pairs of jaws being spaced apart a distance greater than the width of a rail base, each jaw having an undercut gripping face.

5. As an article of manufacture a rail 55 brace comprising an elongated strip and oppositely disposed pairs of jaws integral with the strip, the two pairs of jaws being spaced apart a distance greater than the width of a rail base and having diagonally 60 undercut gripping faces.

6. As an article of manufacture a rail

brace comprising an elongated strip having an opening therein for the reception of securing means, and oppositely disposed pairs of rail engaging jaws upon the strip, the 65 two pairs of jaws being spaced apart a distance greater than the width of a rail base, said jaws having undercut gripping faces.

7. As an article of manufacture a rail 70 brace comprising an elongated strip having an apertured end for the reception of securing means, and oppositely disposed pairs of jaws upon the strip and spaced apart a distance greater than the width of a rail 75 base, said jaws having undercut gripping faces, said strip having an intermediate bent portion and a reinforcing web adjacent thereto.

8. As an article of manufacture a rail 80 brace comprising an elongated strip, rail engaging devices thereon, said strip being bent at an intermediate point, and a reinforcing web adjacent the bend.

9. As an article of manufacture a rail 85 brace comprising an elongated strip, oppositely disposed rail engaging jaws thereon spaced apart a distance greater than the width of a rail base, said jaws having undercut gripping faces, laterally extending 90 ears interposed between and extending beyond the jaws, and means adjustably mounted within each ear for engaging a rail inserted between the jaws.

10. The combination with ties and rails 95 secured thereon; of diagonally disposed braces secured upon the ties and extending under the rails, each brace having spaced jaws engaging opposite base flanges of a rail.

11. The combination with ties and rails thereon; of diagonally disposed brace strips extending over and secured to the ties and projecting under the rails, and spaced jaws upon the strips and having undercut gripping faces frictionally engaging opposite base flanges of a rail.

12. The combination with ties and rails secured thereon; of diagonally disposed 110 braces secured upon the ties and extending under the rails, each brace having spaced jaws engaging opposite base flanges of a rail, and means adjustably connected to each strip for engaging the bottom surface 115 of the rail thereon.

In testimony that I claim the foregoing as my own, I have hereto affixed my signature in the presence of two witnesses.

WILLIAM D. KELLY.
